UNITED STATES PATENT OFFICE.

JOHN W. WEBSTER, OF CHICAGO, ILLINOIS, ASSIGNOR TO DEERING HARVESTER COMPANY, OF CHICAGO, ILLINOIS.

GRAIN-BINDER.

SPECIFICATION forming part of Letters Patent No. 723,955, dated March 31, 1903.

Application filed May 5, 1902. Serial No. 105,935. (No model.)

To all whom it may concern:

Be it known that I, JOHN W. WEBSTER, of Chicago, in the county of Cook and State of Illinois, have invented certain new and useful 5 Improvements in Grain-Binders, of which the following is a full description, reference being had to the accompanying drawings, in which—

Figure 1 is a front end view of an ordinary 10 Appleby binder of the type manufactured by the Deering Harvester Company, showing my improvements; Fig. 2, a similar end view, partly in section, but showing the operative parts in different positions; and Fig. 3 a top 15 view of the same parts.

In the drawings, A is the main binder-frame, U-shaped in form, lying horizontally, as usual.

B is the needle-shaft, and b the needle- 20 crank.

C is the usual knotter driving-shaft.

D is the bevel-gear, having the crank-wrist 25 d, by which the needle is driven.

E is the needle-pitman, extending from the 30 wrist d to the wrist b' on the needle-shaft crank.

F is the compressor-link, of the usual form, generally speaking, but modified somewhat in construction to answer my purposes.

35 G is what is generally termed the "packer-shaft." It is the motor-shaft, as usual, in binders of this class. Upon it is loosely placed the bevel-gear g, and on it is also permanently secured the driver g'. Upon the

35 pinion is the spring-actuated driving-dog g'. Pivoted on the needle-shaft is the detent H, connected to the needle-shaft crank by the usual spring I. Reaching in the opposite direction from the detent H and as one part 40 with it is the stop K.

L is a shaft having upon its lower end the bevel-pinion l, adapted to intermesh with the gear g, and upon its upper end is the pinion l', adapted to mesh into the bevel-gear D.

45 Pivoted in the main frame at m is the compressor-lever M, having upon one end the antifriction-roller m', and pivoted in its upper end at m² the compressor-spring rod f. Upon the gear D is the cam d', which has the promi- 50 nence d².

N is the compressor-shaft, having the crank

n and the wrist on which the compressor-link n' is pivoted. To the said compressor-shaft is secured the compressor-arm O.

Aside from the stop K, all parts so far 55 mentioned do not differ from what is well known in the art.

My improvement consists in the placement of a foot f' on the compressor-link and the stop K upon the detent H, means by which 60 they are made to coöperate and produce the desired result. With the compressor-lever M and the prominence d² of the cam in position shown, downward pressure upon the said lever holds the knotter driving-shaft C from 65 making any retrograde movement. In short, in common parlance the binder is held home. In order to produce downward spring-pressure upon the said lever, I resort to a well-known expedient, which consists in placing a bracket 70 P upon the binder-frame, having a spring-held pin p', which rests upon the lever M, as shown in Figs. 1 and 2. This spring is given sufficient scope to cause the roller m' to press behind the prominence d² when the parts are in 75 the position shown in Fig. 1. The cam d' is made eccentric, so that when the binder is started from its home position (shown in Fig. 1) the compressor-lever M will be moved to draw the compressor, through the instrumen- 80 tality of the spring-link, in the usual manner gradually against the bundle while it is being bound. When the parts are in the position shown in Fig. 1, the foot f' rests upon the stop K of the detent H. If now the compres- 85 sor is moved by the grain pressed against it by the packers, the foot f' will be forced downward upon the stop K and the detent will be raised from its position of rest against the driving-dog g², and the clutching device 90 thus be permitted to engage. When the needle-crank is drawn upward, the stop K is moved away from the foot f' on the compressor-link; but when the needle-crank is returned to its home position and the detent 95 H carried with it, the stop K, being as one piece with the latter, is brought to position to meet the foot f' again, where it remains until the said foot presses downward under the influence of the accumulating bundle. 100 The spring f³ must of course yield when the compressor is moved by the accumulating

bundle. If, however, it is desired to have a weaker spring than that ordinarily used in a compressor-link, the construction of spring-link shown in the patent granted to Charles 5 Whitney, No. 295,510, dated March 18, 1884, may be resorted to. The prominence d^2 is made quite high, so that the compressor-link is drawn well upward for an instant, and the detent H and the stop K are permitted to rise fully to position. The roller m' passing over the prominence permits the link to drop so much as to permit the foot f' to rest upon the said stop K when it is fully in position for performing its office, when the compressor 10 is again moved by the accumulating bundle. In Fig. 2 the cam has reached a position where in its further movement in the direction indicated by the arrow the lever M will permit the compressor to drop, the stop K

being so far out of the way as to permit the 20 same.

What I claim as my invention, and desire to secure by Letters Patent, is—

In a grain-binder, the bevel-gear, a cam integral therewith, a compressor, a compressor-actuating link provided with a foot, a compressor-lever actuated by said cam and adapted to operate said compressor-actuating link, and an oscillating clutch-detent supported upon a stationary pivot and having an arm 25 thereon in such a position as will adapt it to be engaged by the foot of the said compressor-actuating link, all combined substantially as described.

JOHN W. WEBSTER.
